UNITED STATES PATENT OFFICE

GEORGE M. MAIER, OF PELHAM, NEW YORK, ASSIGNOR TO AMERICAN RADIATOR COMPANY, OF NEW YORK, N. Y., A CORPORATION OF NEW JERSEY

DESIGN FOR A CASING FOR A HOT WATER HEATER OR SIMILAR ARTICLE

Application filed November 10, 1931. Serial No. 41,683. Term of patent 14 years.

To all whom it may concern:

Be it known that I, GEORGE M. MAIER, a citizen of the United States, residing at Pelham, Westchester County, in the State of New York, have invented a new, original, and ornamental Design for Casing for a Hot Water Heater or Similar Article, of which the following is a specification, reference being had to the accompanying drawing forming a part thereof.

In the drawing—

Figure 1 is a front elevation of a hot water heater embodying my design, and

Fig. 2 is a top view thereof.

The dominant feature of my present design resides in the forming of the body portion including the base and depending vertical portion of the top with vertical panels which are inwardly curved or concave in cross section.

I claim:

The ornamental design for a casing for a hot water heater or similar article, as shown and described.
